UNITED STATES PATENT OFFICE.

FRANK R. TALBOTT, OF CLEVELAND, OHIO, ASSIGNOR TO THE TALBOTT RUBBER COMPANY, OF CLEVELAND, OHIO, A CORPORATION OF OHIO.

DESIGN FOR A PNEUMATIC-TIRE TREAD.

Application filed October 24, 1921. Serial No. 510,159. Term of patent 3½ years.

To all whom it may concern:

Be it known that I, FRANK R. TALBOTT, a citizen of the United States, residing at Cleveland, in the county of Cuyahoga and State of Ohio, have invented a new, original, and ornamental Design for Pneumatic-Tire Treads, of which the following is a specification, reference being had to the accompanying drawing, forming part thereof.

Fig. 1 is a plan view of a portion of a pneumatic tire tread showing my new design.

Fig. 2 is a section on the line 2—2 of Fig. 1.

I claim:—

The ornamental design for a pneumatic tire tread, as shown.

FRANK R. TALBOTT.
